SELECTIVE TRAVEL DRAFT GEAR WITH INCREASED TRAVEL IN BUFF

David S. Campbell, Glen Ellyn, Ill., assignor to Cardwell
Westinghouse Company, a corporation of Delaware

Application March 23, 1953, Serial No. 344,131

6 Claims. (Cl. 213—44)

This invention relates to draft gears for railroad cars, 15 and has for its principal object to increase the possible travel in buff, and thus give better cushioning to the car and the lading.

Generally speaking, this is accomplished by offsetting the draft gear toward the end of the car to let the couple 20 horn go an increased distance from the striking plate when the draft gear is released.

Further objects and advantages of the invention will 25 become apparent as the description is read in connection with the accompanying drawings, in which:

Fig. 1 is a horizontal section through familiar parts of a freight car showing the draft gear applied;

Fig. 2 is a vertical section of the same;

Fig. 3 is an enlarged horizontal section through the 30 draft gear and portions of the draft yoke, center sills, and draft lugs;

Fig. 4 is a vertical section on the line 4—4 of Fig. 3;

Fig. 5 is a vertical section on the line 5—5 of Fig. 4;

Fig. 6 is a horizontal section showing the relations 35 of the relevant parts in buff;

Fig. 7 is a similar view of the parts in draft;

Fig. 8 is a perspective view of a side bar or thrust 40 column, two of which are used in the draft gear shown;

Fig. 9 is a cross section on the line 9—9 of Fig. 8;

Fig. 10 is a perspective view of the front or outer 45 draft gear housing; and

Fig. 11 is a perspective view of the rear or inner draft gear housing and a shear pin used to hold temporarily the draft gear compressed for handling, shipping, and installing.

But these drawings and the corresponding description 50 are for the purpose of illustrative disclosure only, and are not intended to impose unnecessary limitations on the claims.

In Figs. 1 and 2, the draft gear indicated generally by 10 is shown in the familiar surroundings of center sills 11, draft lugs 12, draft yoke 13, coupler butt or shank 14, draft key 15, coupler carrier iron 16, draft gear carrier iron 17, coupler horn 18, and striking plate 19 (all corresponding to Fig. 10.51 of the Car Builders' Cyclopedias, 1946, p. 944). These parts are so familiar that no specific description is thought necessary.

The draft gear includes filler blocks in the form of an outer or front housing 20, an inner or rear housing 21, a cushioning element 22 between the housings, and side bars or thrust columns 23.

The inner or rear housing includes a rear wall 24 to 55 cooperate with the rear draft gear lugs 12 and a front wall 25 to cooperate with the cushioning element 22, the walls 24 and 25 being connected by side walls 26.

The inner or rear wall 24 is offset forwardly or toward 60 the end of the car as shown at 27 wide enough to receive the draft gear yoke 13, as shown in Figs. 3, 6, and 7.

The front or outer housing 20 includes an inner or rear wall 28 to cooperate with the cushioning element 22 and a front wall 29 to cooperate with the front draft gear lugs 12. The front wall 29 is offset outwardly or

2

toward the end of the car, as indicated at 30, a distance corresponding to the offset 27 and presenting a face 31 to cooperate with the inner end of the coupler butt or shank 14 in buff.

5 The walls 28 and 29 of the front or outer housing 20 are connected by side walls 32 having passageways 33 and grooved channels 34 to receive the forward or outer ends of the side bars or thrust columns 23 and projecting lugs 36.

10 The side walls 26 of the rear or inner housing 21 are provided with passages 37 ending in buttresses 38 and also with vertical openings 39 to receive shear pins 40 adapted to be inserted through the openings 39 and an opening 41 in the rear ends of the side bars 23 to hold the draft gear assembled with the cushioning element 22 under sufficient compression to enable the draft gear to be inserted in the draft gear pocket between the center sills 11 and the draft gear lugs 12.

The cushioning element 22 may be of any selected type, but is here shown as the rubber spring type composed of a plurality of perforated plates 42 and rubber bars 43 on each side of the plates 42 and spacer plates 44. A variety of such rubber spring cushioning elements are known, and no detailed description is deemed necessary. Specifications on the order of those given in Tucker Ser. No. 223,746, filed April 30, 1951, may be used.

15 It will be seen from the drawings (particularly Figs. 1, 2, 3, 6, and 7) that, on account of the offsets 27 and 30 in the housings 20 and 21, the draft gear yoke, and therefore the coupler, is allowed to go endwise to the car an increased distance over that commonly allowed, which spaces the coupler horn 18 an increased distance from the striking plate 19 when the draft gear is in full release.

20 Upon receiving buffing force indicated by the arrow B in Fig. 6, the coupler butt acts against the front face 31 of the front housing 20, forces that housing against the cushioning element 22, and that element in turn against the rear housing 21, and the inner wall 24 which will be held by the inner draft lugs 12. It will thus be clear that in buff the coupler horn can travel an increased distance over heretofore standard practice corresponding to the extent of the offsets 27 and 30. That additional travel, while the cushioning unit is being compressed, provides additional protection of the car and the lading in buff.

25 As shown in Fig. 7, when draft is applied, as indicated by the arrow C, the rear housing 21 moves toward the end of the car while the cushioning unit 22 is compressed until the buttresses 38, striking the inner ends of the thrust members 23, force their outer ends against the front draft lugs 12.

30 In one form of the improved draft gear that has been found satisfactory, the arrangement gives up to 3 1/4" travel in buff as compared with 2 5/8" to 2 3/4" in prior devices, and gives up to 2" travel in draft—in all, a total travel of 5 1/4", which is still less than 5 1/2" now allowed by the Association of American Railroads, and leaves 1/4" travel that makes a great factor of safety with rubber under that state of compression.

35 The draft gear, including the front and rear housings, the cushioning element, and the two side bars 23 are readily assembled under initial compression and made fast by inserting shear pins 40 through openings 39 and 41, when the draft gear will be a unit for storing, shipping, handling, and is readily inserted into the draft gear pocket and supported by the draft gear carrier. The first considerable shock will shear the pins 40 and release the parts for normal operations described.

40 The key to the longer travel in buff lies in letting the draft gear yoke and the coupler go forward or outward

and space the coupler horn farther away from the striking plate than is possible in prior devices. Offsetting or notching the inner housing is a simple way to permit the increased travel in release, and offsetting or extending the front housing beyond the faces of the front draft lugs makes the cushioning element move the coupler forward in release and resist reverse movement in buff. Many equivalent expedients will give like results.

Embodiments of this invention, either with a rubber cushioning element or any other, are interchangeable with standard equipment, because the draft gear pocket remains the same.

In the particular construction shown in the drawing, and more particularly in Figs. 1, 3, 6, and 7, the rubber cushioning element of suitable capacity does not require the full length of the standard draft gear pocket, and the excess is taken up in the housings 20 and 21. If a suitable friction or other cushioning element replaced the rubber spring element 10, there might be less requirement for taking up space in the corresponding housings or followers.

The space between the center sills of the car and the distance between the faces of the draft gear lugs is set by requirements of the Association of American Railroads, and fixes the size of the draft gear pocket for cars used in interchange. The particular embodiment of the invention shown in these drawings fits this novel draft gear into that pocket, and furnishes the extra travel described. In embodying other cushioning elements, the disclosure will furnish sufficient guide.

I claim:

1. In a draft gear having a striking plate, the combination of a pair of thrust bars, inner and outer housings therefor, with a cushioning element operatively positioned between the housings, the inner face of the inner housing being offset toward the cushioning element wide enough to receive a draft gear yoke, and the outer face of the outer housing being offset outwardly away from the cushioning element an amount corresponding to the offset of the inner housing, whereby upon release of the draft gear an associated draft gear yoke and coupler having a horn may go outwardly an increased distance corresponding to the offsets in the housings and provide a correspondingly additional travel of the coupler horn to the striking plate under buff.

2. In a draft gear, the combination of a pair of thrust bars, inner and outer housings therefor, means connecting one end of each thrust bar to one of the housings, and a cushioning element operatively positioned between the housings, the inner face of the inner housing being offset toward the cushioning element wide enough to receive a draft gear yoke, the outer face of the outer housing being offset outwardly away from the cushioning

element an amount corresponding to the offset of the inner housing, and means to hold the same assembled with the cushioning element under enough compression to bring the draft gear within the length of the draft gear pocket, said last named means comprising shear pins extending through aligned holes in the other ends of the thrust bars and the other housing.

3. In a draft gear, inner and outer housings, a cushioning element operatively positioned between them, the inner face of the inner housing being offset toward the cushioning element wide enough to receive a draft gear yoke, the outer face of the outer housing being offset outwardly away from the cushioning element an amount corresponding to the offset of the inner housing, sides of said housings having aligned passages, and thrust means in said passages comprising bars each having one end connected to one of said housings and having its other end engageable by the other housing on compression of the cushioning element.

4. In a draft gear, inner and outer housings, a cushioning element operatively positioned between them, the inner face of the inner housing being offset toward the cushioning element wide enough to receive a draft gear yoke, the outer face of the outer housing being offset outwardly away from the cushioning element an amount corresponding to the offset of the inner housing, said housings having aligned passages, thrust bars in said passages with one end of each connected to one of said housings, and shear means fastening the other end of each thrust bar to the other housing.

5. In a draft gear, an inner housing having a portion of its inner face offset outwardly along a transverse distance wide enough to receive the outer face of the inner end of a draft gear yoke, and having a passage in each of its sides each of which is open at one end to receive the end portion of a thrust column and closed at its other end by a buttress for the terminal end of said thrust column.

6. In a draft gear, a front filler block having a rear wall adapted to engage a cushioning element and a front wall adapted to engage draft lugs, said front wall having a forwardly offset area adapted to be engaged by a coupler butt.
